CLAIM

The ornamental design for a hair styler, as shown and described.

DESCRIPTION

FIG. 1 is a top front and right side perspective view of a hair styler, showing my design;

FIG. 2 is a front view of the appliance of FIG. 1;

FIG. 3 is a right-side view of the appliance of FIG. 2;

FIG. 4 is a left-side view of the appliance of FIG. 2 shown in an inverted position;

FIG. 5 is a rear view of the appliance of FIG. 2;

FIG. 6 is a top plan view of the appliance of FIG. 2; and,

FIG. 7 is a bottom plan view of the appliance of FIG. 2.

The cord is shown partially broken away in the various views to indicate indeterminate length.
